GATE FOR RAILROAD CROSSINGS AND PEDESTRIAN CROSSINGS

Application filed December 19, 1930. Serial No. 503,464.

This invention is for a gate for railroad crossings and pedestrian crossings, and has special reference to a gate adapted for protection of vehicular and pedestrian traffic at railroad and similar crossings as also for the protection of pedestrian traffic at school crossing lanes.

The primary object of the invention is to provide a gate which may be actuated by an electrical source of power for railroad crossings, or may be provided with manually operated means at school crossing and similar lanes of pedestrian traffic.

Another object of the invention is to provide a resilient obstruction at such crossings, which will serve mainly as a visual warning, and which in the event of collision of an automotive vehicle therewith will not result in damage of any extent to either the gate or vehicle.

A further object of the invention is to provide a gate of the lazy-tongs type, the joints of which are vertically hinged and permit the gate sections to swing with the movement of the vehicle, spring means being employed at the hinge joints to return the sections to a normally projected position.

Other objects and advantages of the invention will become apparent as the following description is read on the drawings forming a part of this specification.

The invention consists primarily of a gate of the lazy-tongs type disposed in a housing and adapted to be projected therefrom by electrically actuated or manually operated means, the tongs having the rest or supporting leg of greater length than the actuated leg, and the terminal joints being provided with spring hinges, whereby sag of the gate may be obviated, and the gate may be swung about a horizontal plane about each section thereof.

The invention is adequately illustrated in the accompanying drawings in which:

Fig. 1 is an elevation of the gate in retracted position and disposed in a housing shown in section;

Fig. 2 is an enlarged view showing one of the spring hinged connections between two sections of the gate;

Fig. 3 is a section taken on line 3-3 of Fig. 2;

Fig. 4 is an elevation of the manually operated gate intended for school and similar crossings;

Fig. 5 is an elevation showing a pair of extended cooperating gates in operative position.

Similar reference characters are used to designate similar parts throughout the several views.

The invention consists of a gate of the lazy-tongs type constructed of a plurality of sections hingedly connected by means of spring hinges formed of a pair of cooperating leaves 10 having cooperating ears 11 and 12 integral therewith, said ears having aligning apertures cooperating with a hinge pin 13 around which is disposed a torsion spring 14 having the opposite extended ends 15 and 16 cooperating with the leaves 10, the leaves being formed in abutting relation, as at 17, between the ears 12 and resiliently retained in such relation by the springs 14. Tubular members 18 and 19 are connected by welding or other suitable means to the leaves, the members 19 being slidable within the members 18, and forming telescopic aligning members.

The levers 20 and 21 are pivotally connected to the leaves 10 by means of rivets or bolts 22, and are provided with sleeve bushings 23. Levers 20 and 21 are intermediately pivotally connected by rivets or bolts 24. The terminal actuating lever 25 is pivotally connected to a screw actuated arm 26 which is slidably mounted on a vertical rod 27 and threadedly mounted on a screw 28, the hub 29 having internal threads cooperating with the threads on the screw 28, and hub 30 having a bore to slidably fit the rod 27.

The supporting or rest leg 31 is made of a length greater than the actuating lever, as indicated, and is pivotally connected to an adjustable shoe 32 as at 33, the shoe being adjustable longitudinally of the lazy tongs and in a horizontal plane.

Vertical rod 27 is anchored to the top and bottom of the housing 34 as indicated at 35 and 36, and disposed parallel to the actuating

screw 28 and spaced therefrom. The actuating screw 28 is mounted in bearings 37 and 38 fixed to or integral with housing 34, and has fixedly mounted thereon a worm gear 39 which cooperates with a worm 40 mounted on the shaft of a reversible motor 41, which in turn is suitably mounted on a pedestal or bracket 42 within the housing 34.

A modification of the invention is indicated 10 in Fig. 4 in which the usual type of lazy tongs, consisting of terminally connected crossed levers 20 and 21 are intermediately pivoted as at 24, the terminal pivots 43 being preferably bushed, there being no difference 15 in the construction of levers 20 and 21 over that shown in Fig. 1. Also, the actuating arm 25 and the supporting leg or rest 31 are similar in both cases, being respectively pivotally connected to the actuating arm 26 as at 20 44, which in turn is slidably mounted on the rod 27 and threadedly mounted on the screw 28, a bearing bracket 45 suitably supporting the lower end of shaft 27 and screw 28, and to a shoe 46 which is slidably mounted on a 25 ways 47 and fixedly secured in adjusted position by a set screw 48.

A bevel gear 49 is fixed to the shaft end of screw 28 and meshes with a bevel pinion 50 fixedly secured on a shaft 51 which is rotatably mounted in the bearing 52 which is integral with the housing 53, shaft 51 having a crank extension 54 for manual operation of the lazy-tongs.

The operation of the device as indicated 30 in Fig. 1 is as follows. A suitable source of electric power is provided for the motor 41 and controlled by any known means such as a reversing switch in combination with a circuit closing switch, or a double pole double 35 throw switch connected for reversal of the motor, or in combination with a train controlled circuit similar to the well known block signal systems.

Closing of the circuit to the motor 41 causes 40 the armature and coincidentally the shaft with worm 40 to rotate, driving the worm gear 39, and coincidentally rotating screw 28, which causes the actuating arm 26 to travel downwardly pulling down on lever 25 and thereby 45 projecting the lazy-tongs as indicated in Fig. 6. The adjustable shoe 32 permits adjustment of the pivotal point 33 to compensate for sag in the extended lazy-tongs. When in the extended position, should a vehicle collide with the device, the sections would pivot 55 about the hinge joints 13, and be resiliently urged to return to normal position by springs 14, and stopped in such position by the co-operating edges 17 of the hinge leaves 10.

The modification shown in Fig. 4 may be 60 constructed as shown or may be of the spring hinge construction shown in Fig. 1, and is indicated as manually operated by means of the crank 54 driving the screw 28 through 65 the cooperating bevel gears 49 and 50. To

retract the device, the crank 54 is rotated in the opposite direction, or the motor 41 is reversed, causing the arm 26 to travel upwardly.

It will be noted that variations in construction and arrangement which are consistent with the meaning and scope of the appended claims may be resorted to without detracting from the spirit or scope of the invention or sacrificing any of its advantages.

We are aware that crossing gates of the lazy-tongs type have been made, therefore we do not claim such a combination broadly, but we do claim:

1. In combination, a lazy-tongs consisting of a plurality of resiliently restrained hingedly connected sections, means for preventing sag or drop at the hinge joints, and means for actuating said lazy-tongs.

2. In combination, a lazy-tongs, consisting of a plurality of resiliently restrained, hingedly connected sections, each section consisting of a pair of centrally pivoted levers, the ends of which are pivotally connected to the hinge leaves, telescopic aligning members between opposite hinges and fixedly secured thereto, the depending terminal lever at one end of said lazy-tongs being of greater length than said centrally pivoted levers, and being pivotally mounted on an adjustable support, the opposite terminal lever being connected to vertically traveling actuating means for extending and retracting said lazy-tongs.

3. In combination, a lazy-tongs consisting of a plurality of resiliently restrained hingedly connected sections, each section consisting of a pair of levers pivotally connected at their centers, the ends thereof being pivotally connected to hinge leaves, said hinge leaves being pivotally connected to the leaves of an adjacent section, telescopic aligning members fixedly secured to opposite hinges, the depending terminal lever at one end being of greater length than the levers forming the balance of said lazy-tongs and being pivotally mounted on an adjustable support, the opposite terminal lever being pivotally connected to a vertically movable arm actuated by a cooperating rotating screw.

4. In combination, a lazy-tongs consisting of a plurality of pairs of levers, each pair being pivotally connected at their centers, the end of each of said levers being pivotally connected to the leaf of a hinge, the cooperating hinge leaf being connected to the adjoining section, a spring cooperating between the leaves of each hinge, each of said leaves having affixed thereto a member of a telescopic aligning element adapted to cooperate with the member affixed to the leaf of the opposite hinge, said levers being of uniform length except one depending terminal

lever, said one lever being of greater length and pivotally mounted in an adjustable support, the opposite terminal lever being pivotally connected to actuating means for extending and retracting said lazy-tongs, said hinge leaves being cooperatively formed to align said sections against the action of said springs.

5. A crossing gate comprising, in combination, a lazy-tongs, a housing therefor, said lazy-tongs consisting of a plurality of sections hingedly connected and resiliently aligned and terminating in a pair of terminal levers, telescopic aligning means cooperating between opposite hinges, and screw actuated means cooperating with one terminal lever for extending and retracting said lazy-tongs.

6. A crossing gate comprising, in combination, a lazy-tongs, a housing therefor, said lazy-tongs consisting of a plurality of sections hingedly connected and resiliently aligned, each section consisting of a pair of levers pivotally connected at their centers, and being pivotally connected at their ends to the leaves of hinges, said leaves having fixedly secured thereto in cooperative relation, telescopic aligning members adapted to prevent drop between adjacent sections, and being formed with abutting edges, and springs cooperating between said leaves, one depending terminal lever being of greater length than the balance of the levers and being pivotally mounted on an adjustable support, the opposite terminal lever being pivotally connected to a screw actuated arm, a rotatable screw cooperating therewith, and means for rotating said screw.

40 In testimony whereof we have affixed our signatures.

FRANCIS W. McFARLAND.
